The ornamental design for an optical eyewear display, as shown and described.

DESCRIPTION

FIG. 1 is a front perspective view of an optical eyewear display.

FIG. 2 is a front view of the optical eyewear display shown in FIG. 1.

FIG. 3 is a rear view of the optical eyewear display shown in FIG. 1.

FIG. 4 is a left side view of the optical eyewear display shown in FIG. 1.

FIG. 5 is a right side view of the optical eyewear display shown in FIG. 1.

FIG. 6 is a top view of the optical eyewear display shown in FIG. 1; and,

FIG. 7 is a bottom view of the optical eyewear display shown in FIG. 1.

The broken lines illustrate the design's environment and form no part of the claimed design.
